UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 25,691, dated June 30, 1896.

Application filed May 29, 1896. Serial No. 593,673. Term of patent 14 years.

To all whom it may concern:

Be it known that I, WILLIAM C. CODMAN, of Providence, in the county of Providence and State of Rhode Island, have invented and produced a new and original Design for a Handle for Spoons, Forks, and Similar Articles; and I hereby declare that the following is a full, clear, and exact description of the same, reference being had to the accompanying drawings, forming part of this specification.

Figure 1 is a front view of my newly-designed handle, shown in connection with the bowl of a spoon in solid lines, a fork being indicated in broken lines. Fig. 2 is a view of the reverse of the handle, shown in connection with the bowl of a spoon.

The leading features of my design consist in the marginal border of the handle, wider at the upper part of the handle and gradually narrowing toward the lower end of the handle, where the marginal lines terminate in a scroll, the foliated leaf ornamentation at the upper part, and the beads placed between the foliations at the upper part and diminishing in diameter extend to the lower end.

In Fig. 1, A indicates the central panel, which has a raised convex surface, a round upper end, and gradually diminishes in width to a thin stem at the neck of the spoon, giving to the panel the appearance of a long Ruberts drop or a pearl pendant. The marginal border B surrounds the panel A. It is wider at the upper part of the handle and gradually diminishes in width toward the lower end. This border B is ornamented at the upper end of the handle by the scroll 3, the two ends of which nearly meet in the center and support a three-branched leaf ornament. On each side of the upper center or-

nament 3 the scrolls 4 extend in opposite directions along the margin of the handle with the leaves 5 5 curving inward diagonally across the border B toward the panel A, the ends of the scrolls terminating in the leaves 45 5. Between the leaves 5 5 are placed the balls or beads 7, and below the leaves the beads 7 continue along the marginal border, diminishing in diameter as the border diminishes in width, to the lower end of the handle, and from the scroll formed at the end of the marginal border B the foliations extend upward, inclosing the center ornament 9.

On the reverse side, Fig. 2, the marginal border B is repeated, but terminated at the 55 upper end in the scrolls 10, between which the ornament 11, consisting of a cluster of curved bars, is placed.

From the lower end of the handle a foliation 12 extends over the body of the bowl of 60 the spoon or other article. The central panel C of the reverse side of the handle differs essentially from the panel A on the obverse of the handle. It is merely the flat space inclosed by the marginal border B and to the eye does 65 not convey the idea of the long drop-shaped pendant so distinctly represented by the panel A.

Having thus described my invention, I claim as new and desire to secure by Letters 7c Patent—

The design for handles for spoons, forks and similar articles herein shown and described.

In witness whereof I have hereunto set my 75 hand.

WILLIAM C. CODMAN.
